CLAIM

The ornamental design for a mobile showroom, as shown and described.

DESCRIPTION

FIGS. 1-3 are perspective views of a mobile showroom of my design;

FIG. 4 is a right-side view thereof;

FIG. 5 is a left-side view thereof;

FIG. 6 is a front view thereof;

FIG. 7 is a rear view thereof;

FIG. 8 is a top view thereof;

FIG. 9 is a top view thereof with the top removed to illustrate the interior; and,

FIG. 10 is a perspective view thereof, with the door in an opened position.

The broken lines illustrate structure or features which form no part of the claimed design.

1 Claim, 6 Drawing Sheets
